UNITED STATES PATENT OFFICE.

VINZENZ M. VACEK, OF VIENNA, AUSTRIA-HUNGARY.

GAME APPARATUS.

1,016,187.

Specification of Letters Patent.

Patented Jan. 30, 1912.

Application filed December 31, 1910. Serial No. 600,338.

To all whom it may concern:

Be it known that I, VINZENZ M. VACEK, a subject of the Emperor of Austria-Hungary, and a resident of Vienna, Austria-Hungary, have invented a new and Improved Game Apparatus, of which the following is a full, clear, and exact description.

The invention relates to game apparatus of the chess type, and its object is to provide a new and improved game apparatus, designed for use by two players and simulating a battle by the employment of game pieces representing military forces.

For the purpose mentioned, use is made of two equal sets of game pieces, adapted to be moved over a game board divided into ninety-nine squares, each set of game pieces representing a queen, a general, two forts, light and heavy infantry, light and heavy cavalry, artillery, rapid fire guns, an aerial vessel or aviator, scouts, and a bridge.

A practical embodiment of the invention is represented in the accompanying drawings forming a part of this specification, in which the figure is a perspective view of the game apparatus.

The game board A is divided into ninety-nine squares, nine running longitudinally and eleven transversely, with the players seated on the longitudinal sides of the game board. The squares are preferably indicated along the longitudinal sides by the consecutive numerals from 1 to 11, and along the ends by the consecutive letters of the alphabet from a to i, as will be readily understood by reference to the drawing. Two of the squares (3^e and 4^e) represent hazards or obstructions of any desired form. Two sets of different-colored game pieces B, B' are employed and set up on the opposite sides of the game board A, as indicated in the figure, each set of game pieces comprising a queen, two forts, two heavy cavalry, two light cavalry, a bridge, an aviator, two artillery, one general, two rapid fire guns, eight light infantry, three heavy infantry and two scouts, the game pieces being set up as indicated in the figure.

The players alternately make each a move with a game piece according to the following rules: The queen moves in all directions, that is, from one square to another, straight, sidewise, or diagonally forward or backward, provided the adjacent square is not occupied by another game piece. The queen does not take or capture other game

pieces. If, however, the queen is captured then the corresponding player has lost the game. The fort moves in all directions, straight and diagonally, to the next square but does not capture. If the fort is adjacent to the queen then it protects the same from the corresponding side against each other game piece. The fort can be taken by the artillery and from other game pieces but cannot be taken by any piece when adjacent to the queen. The heavy cavalry moves two squares in all straight directions, irrespective of whether the squares are occupied or not by other game pieces, and then one square sidewise, and may capture another piece at this latter square. The light cavalry jumps two to three squares in all diagonal directions, irrespective of whether they are occupied or not by other game pieces, and one square diagonally sidewise, at which it captures, but only in case it moves over three squares onto the fourth one. The fort and the hazard on the game board do not permit the advance of the cavalry, that is, they cannot move over squares occupied by the forts nor over the squares containing the hazards. The bridge moves only one square in all straight directions upon unoccupied squares and does not capture, and only when this bridge spans a hazard can the other game pieces cross the hazard by the use of the bridge. The aerial vessel can always pass the hazard. The bridges of both players may occupy both hazards at the same time. The aerial vessel moves in all straight and diagonal directions in case none of the game pieces occupies one of the squares, and it captures sidewise from the direction in which it is moved except the queen, the bridge and the forts. The artillery moves in a straight direction forward, backward and sidewise, in case the squares are not occupied, and captures whatever is found on the last square. The rapid fire guns move in all diagonal directions in case no other game pieces are in their path and capture in the last square. The general moves in all straight and diagonal directions in case no other game piece is in its path and captures whatever it finds on the square. The light infantry moves one square forward and takes the enemy's piece in the next move. The scouts move one to two squares forward in a diagonal direction, and captures the same as the

light infantry. The heavy infantry moves to the next square in every direction and captures whatever it finds in its path. None of the game pieces is compelled to 5 capture. The hazard can only be crossed by the aerial vessel, and the other game pieces only in case the bridge of the corresponding player extends across a hazard.

The game pieces are shown as blocks with 10 the name of the force appearing thereon, but in practice the game pieces are preferably shaped to symbolize the forces they represent.

Having thus described my invention, I 15 claim as new and desire to secure by Letters Patent:

1. A game apparatus comprising a game board divided into a plurality of squares, certain of which are marked to denote hazards, and game pieces comprising the different divisions of an army, certain of 20 which represent artillery, cavalry and infantry movable over the board around the hazards, and certain others of which represent 25 crafts navigable in the air and thus movable over the board and the hazards.

2. A game apparatus comprising a game board divided into a plurality of squares, certain of which are marked to denote hazards, and game pieces comprising the dif- 30

ferent divisions of an army, certain of which represent artillery, cavalry and infantry movable over the board around the hazards, certain others of the game pieces representing crafts navigable in the air and thus movable over the board and the hazards, and certain others of the game pieces representing bridges adapted to span the hazards and permit of the passage there-over of game pieces of the first mentioned 40 divisions.

3. A game apparatus, comprising a game board, divided into ninety-nine squares, of which two adjacent squares represent hazards, and two equal sets of game pieces 45 adapted to be moved over the said squares and representing military fighting pieces, each set of game pieces comprising a queen, general, forts, infantry, cavalry, artillery, aerial vessels, rapid fire guns, a scout, and a 50 bridge adapted to span the hazards for the passage of the other game pieces over the said hazards.

In testimony whereof I have signed my name to this specification in the presence 55 of two subscribing witnesses.

VINZENZ M. VACEK.
